UNITED STATES PATENT OFFICE

VICTOR S. THARP, OF ELMHURST, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

MEASURED SERVICE TELEPHONE SYSTEM

Application filed January 17, 1931. Serial No. 509,330.

The present invention relates to measured-service telephone systems, but more particular to automatic measured-service telephone systems of the type commonly known as booster-battery measured-service systems.

The principal object of this invention, briefly stated, is the provision of a booster battery measured-service telephone system in which the coin-collect operation in connection with paystation apparatus, as well as the operation of the regular subscribers' call meters, is controlled by booster battery.

In present automatic measured-service telephone systems, wherein a regular subscriber's meter is operated by a booster-battery impulse supplied by the final switch of the switch train responsive to the answering of the called party, it is the practice to provide paystation apparatus, such as a paystation repeater, which is prepared for the coin-collect operation by the reversal of the battery feed by the final switch when the called party answers, the collecting operation taking place upon the termination of the connection. In all telephone systems there are many calls for which no charge is made, such as calls to the employees of the telephone company. In order to take care of this requirement in automatic telephone installations, special groups of automatic switches are provided. In a system such as that just described, the final switches, commonly known as connector switches, or just connectors, are provided which will omit the booster-battery impulse to prevent operation of a regular subscriber's meter when such a free call is made, and which will omit the reversing of the battery feed to the calling line to prevent the operation of the paystation repeater in its coin-collect function when the free call is from a paystation. One switch can be provided for both of these omissions.

However, when a call is initiated from a manual position, such as a toll operator's position, it is necessary to provide a connector switch which will reverse the battery feed for all types of calls in order that the manual operator may have answering super-

vision. This requires another special group of connectors for extending calls from manual positions.

It will be appreciated that, by providing a paystation repeater controlled in coin-collect operations by booster-battery impulses, the number of groups of switches for such free-call requirements can be reduced since one group of connector switches which omit only the booster-battery impulse can be employed for the three classes of calls just mentioned. Thus, in systems having free service as previously mentioned, and the regular measured service, it is necessary to provide only two groups of connector switches, one group for regular service which transmits booster-battery impulses for meter operations or coin collections and reverses battery feed for manual supervision, and another group of connectors which omits the booster battery, but reverses the battery feed for manual supervision.

Features of the system to be described subsequently, such as improved impulsing circuits, the arrangement whereby such calls as fire and police calls can be made without depositing a coin when the calls are initiated at paystations, the arrangement whereby it is impossible to extend a call beyond a certain point on regular paystation calls if a coin has not been deposited, the metering of all completed calls over a paystation line, and others not specifically mentioned, are the same as those disclosed in the United States Letters Patent No. 1,644,968, issued on October 11, 1927 to John Wicks, while the paystation repeater of the present invention may be considered as an improvement of the paystation repeater of said Wicks patent.

There are other objects and features of the invention not now specifically mentioned which will be described together with the foregoing, hereinafter with reference to the accompanying drawings.

Referring now to the drawings comprising Figs. 1 to 3, inclusive, the general scheme diagrammatically shown therein may be briefly described as follows: the substation A, Fig. 1, is of the ordinary auto-

matic type having the usual talking instrumentalities and an impulse sender, or calling device, S1. Being a measured-service substation, there is also provided at substation A, a well-known type of coin-collecting mechanism which may be of the type shown and described in United States Letters Patent No. 1,043,219, issued November 5, 1912 to O. F. Forsberg.

- 10 The line conductors 11 and 12 extend from the paystation A to the exchange, terminating at the latter point in an individual trunk-selecting switch, or lineswitch, C. This switch is of the well-known rotary type in which the wipers have no normal position, always remaining in engagement with the bank contacts associated with the trunk line last used, and the function of which it is to extend the line when calling 15 to a trunk line which terminates in an idle selector switch. One of the trunk lines, to which the lineswitch C has access in common with a plurality of other lineswitches, is shown extending to the selector E1, Fig. 3. 20 The relay equipment in Fig. 2 indicated by the reference character D is a repeater, and there is one such repeater inserted in each selector trunk to which the lineswitches of the paystation lines have access. Associated 25 with the repeater are the alarm signal and supervisory circuits shown in Fig. 2A which perform the function of notifying the attendant in the exchange immediately anything goes wrong with the repeater D. 30 The substation A2, Fig. 3, is one of a plurality of substations which are provided for the regular subscribers and has the usual talking instrumentalities and the impulse sender, or calling device, S2. The line connecting the substation A2 with the exchange terminates at the exchange in the lineswitch C2 which is similar to the lineswitch C and is individual to the line of substation A2. 35 Associated with the lineswitch C2 is the booster-battery-operated call meter M which is well known in the telephone art and which needs no further description than to say that it is operated by a booster-battery impulse to register a completed call. 40 The function of the lineswitch C2 is to extend the line of substation A2 when a call is initiated thereat to the group of selector switches of which the selector E2 is one. 45 An operator's position is represented by 50 the jack J and the trunk connecting this position and the automatic exchange terminates in the exchange in the lineswitch C1, the function of which it is, when the operator inserts a plug in the jack J, to extend 55 the operator's trunk to the selector switch E2 or a similar selector switch. The operator's position is provided with a calling device, not shown, which is similar to the calling devices S1 and S2 and by means 60 of which the operator operates the switches 65

to extend calls to the substations in the automatic exchange.

The selector switches E1 and E2 are the first in the series of numerical switches which, in the present showing, include also 70 the connector switches H and H1, and which are employed to complete talking connections between calling and called subscribers. In systems employing first and second selectors, or even third selectors, the selectors E1 75 and E2 will be the first selectors.

These selectors E1 and E2 are of the well-known Strowger vertical and rotary type, and have access to trunk lines extending to groups of connectors represented by connectors H and H1. The selector E1 is a special selector and is accessible only to paystations such as substation A, it is special in that a high resistance is included in the release trunk of the switch for a purpose 80 which will be explained subsequently. A selector of this character is shown and described in the aforementioned Wicks patent. The selector E2 is a regular selector and differs from the selector E1 only in that the high resistance has been omitted from the release trunk. Since Strowger selector switches are well known to those skilled in the art of automatic telephony, the selectors E1 and E2 have not been shown in detail 85 but represented by rectangles. 90

The connector H is one of a group of similar connectors accessible to the selectors E1 and E2 and is of the well-known Strowger vertical and rotary type. Connector H is 100 arranged to reverse the battery feed through the preceding switches and to transmit a booster-battery impulse through the selectors, when a called party responds, to operate the meter M when a call is extended 105 from the substation A2 and to control the repeater D to initiate the coin-collect operation when the call is extended from the paystation A. This connector has access to the lines of substations such as substation A3, 110 for calls to which a charge is made.

The connector H1 is similar to the connector H except that the means for transmitting a booster-battery impulse has been omitted from this connector. This connector has access only to the telephones of 115 officials and employees of the telephone company for calls to whom no charge is to be made.

To those versed in the art of automatic telephony, a connector switch such as H is known as a booster-battery connector, while one such as H' is known as a regular reverse-battery connector.

It is customary in automatic telephone exchanges to provide a special group of second selectors which have access to trunks for fire and police calls, recording operators and such, which type of calls may be initiated from paystations without it being 125 130

necessary for the calling party to insert a coin in the coin-collect mechanism at the paystation to complete the call. These selectors have not been shown on the drawings, but, merely indicated by an appropriate legend since they do not constitute a part of this invention. They have been mentioned merely to explain the purpose of the resistance in the release trunk of the selector 10 for E1 when the time comes. These selectors may be identical to the selector E1 and function in a manner described in the aforementioned Wicks patent.

In order to explain the operation of the circuits, it will first be assumed that a party wishes to extend a call from paystation A to substation A3 and that the party attempts to do so without first depositing a coin in the coin-collect mechanism at the 20 paystation.

When the receiver is removed at substation A, the line relay 26 of the individual lineswitch C is energized over the two sides of the calling line in series. Relay 26, upon 25 operating, at its armature 40 completes a circuit which includes the switching relay 25 and the motor magnet 27 in series, and at its armature 39, connects the test wiper 46 to the above circuit at a point mid-way between the switching, or cut-off, relay 25 and said motor magnet. The operation of the lineswitch C depends upon whether the trunk line with which its wipers 44 to 47, inclusive, are in engagement is busy or not. 35 Assuming this trunk line to be busy, there will be a ground potential present upon the test contact engaged by the test wiper 46, the switching relay 25 will be short-circuited, and the motor magnet 27 will be supplied 40 with direct ground by the test wiper and will operate as a buzzer to advance the switch wipers step by step in search of an idle trunk line. However, it will be assumed in the present case that when the receiver is

45 removed at substation A, the switch wipers 44 to 47, inclusive, are in engagement with the bank contacts associated with an idle trunk line. Under these conditions, immediately following the energization of the line 50 relay 26, the switching relay 25, not being short-circuited, will energize. Upon energizing, relay 25 disconnects the line conductors 11 and 12 of the calling substation from the winding of the line relay 26 and from 55 ground, respectively, and extends them by way of armatures 33 and 36, wipers 44 and 47, bank contacts 52 and 55, conductors 48 and 51, armatures 145 and 144 and their resting contacts, armatures 160 and 164 and 60 their resting contacts, upper and lower windings of the differential relay 130, and thence through the winding of the line relay 135 and the winding of the impedance coil 139 to battery and ground respectively. The 65 line relay 135 of the repeater D, Fig. 2, is

energized over the two sides of the calling line in series and at its armature 183 completes the circuit of the slow-to-release relay 136 from ground by way of armature 162 and resting contact of relay 128. Relay 136 thereupon energizes and, at its armature 186, places ground on release-trunk conductor 50 by way of the retardation coil 138, thereby establishing a holding circuit for lineswitch C which extends by way of bank contact 54, wiper 46, armature 35 and its make contact, winding of relay 25, and thence through the winding of motor magnet 27 to battery. It will be understood that this holding circuit is completed before the slow-to-release relay 26 has had time to deenergize after its circuit was opened by relay 25. A branch of the holding circuit also extends by way of private normal conductor 30 to the multiplied test contacts in the banks of connector switches which have access to the line of substation A, whereby that line is protected from intrusion in the well-known manner. It will be remembered that ground is supplied to the release-trunk conductor 50 through the retardation coil 138. This coil is of a very low resistance, of about two and one half ohms, so that the multiples of the test contacts accessible to other lineswitches are made busy. 95

Relay 136, upon energizing, also completes at its armature 188 a circuit for the polarizing winding of the electro-polarized relay 132 in series with the winding of relay 141. The electro-polarized relay 132 is so adjusted that current flowing in its polarizing winding does not cause this relay to operate its armature, though after once operating, the current flow in the polarizing winding is sufficient to maintain the armature attracted. Relay 141 is, therefore, the only relay operated in this circuit. Relay 141, upon energizing, opens a point in a certain shunt circuit which will be described later. 100

When the line relay 135 of the repeater D energizes, a bridge circuit is closed across the trunk conductors 200-202, which may be traced as follows: conductor 200, normally-closed contacts controlled by armature 172 of relay 131, armature 190 and its resting contact, normally-closed contacts controlled by armature 160, upper winding of relay 133, make contact and armature 184 of line relay 135, normally-closed contacts controlled by armature 164, normally closed contacts controlled by armature 173, lower winding of relay 132, to the conductor 202. Upon the closure of this bridge circuit, the line relay of the selector E1 is energized. Upon energizing that line relay completes the circuit of the slow-acting release relay of the selector E1 which latter relay immediately operates to prepare the operating circuits of the selector E1 in the usual manner and to place ground on the release-trunk conductor 110

201 through the previously-mentioned high resistance with which the selector E1 is equipped. This ground extends back over the release-trunk conductor 201 to the polarizing winding of the relay 132 in the repeater D. The relay 141 is not short circuited at this time as the resistance in the release trunk of the selector E1 is high enough to prevent the relay winding from 5 being shunted. Ground is now supplied to the polarizing winding of relay 132 from the selector E1 and from the repeater D.

Before proceeding further with the explanation, attention is called to a shunt circuit 10 around armature 184 and its front contact which, it may be mentioned, are the impulse springs of the repeater D which control the operation of the selector E1 and the succeeding switches. This shunt circuit extends as 15 follows: from armature 184 by way of back contact and armature 196, armature 180 and its back contact, armature 189 and its front contact, to the front contact of armature 184. The contacts at armatures 180 and 189 are 20 closed, but, since relay 141 is energized, armature 196 will be in an attracted position and the shunt circuit will be opened at that point, it being clear from this explanation that the shunt circuit will not interfere with 25 the operation of the impulse springs, represented by armature 184 and its working contact, in repeating impulses.

The calling subscriber at substation A may 30 now operate his calling device in accordance 35 with the first digit of the number which it is necessary to call in order to obtain connection with the substation A3. By the operation of the calling device S', a series of 40 interruptions is produced in the circuit of the line relay 135, thereby causing this relay to deenergize in response to such interruptions, each time opening the previously-traced bridge circuit of the line relay of the selector E1. The selector E1 thereupon functions 45 in the well-known manner to elevate its wipers opposite the level of bank contacts represented by the number of impulses comprising the first digit and then automatically rotates its wipers to select a trunk leading to 50 an idle connector such as the connector H. Inasmuch as the connector H is shown as accessible to the selector E1 over the ninth level of bank contacts, it necessarily follows 55 that the first digit which the subscriber dials is nine. The test wiper of the selector E1 will encounter ground on the test contacts of the busy connectors of the group, but will come to rest in the well-known manner when an idle connector is found.

60 Assuming that the connector H is the first idle connector of the group to be found, when the wipers of the selector E1 are placed in engagement with the bank contacts to which the conductors 203 to 205, inclusive, 65 are connected, the test wiper of the selector

will not encounter ground on the conductor 204 and the selector will thereupon function in the well-known manner to extend the trunk conductors 200 to 202, inclusive, to the bank multiple conductors 203 to 205, inclusive. When this is done, the line relay 215 of the connector H energizes over the following circuit; from ground, through the upper winding of relay 215, normally-closed contacts controlled by armature 252 of the back-bridge relay 249, line conductor 212, multiple conductor 203, upper line wiper and line conductor through the selector E1, trunk conductor 200, thence over the previously-traced bridge circuit in the repeater E to the trunk conductor 202, lower line conductor through the selector E1 and the lower line wiper, conductor 205, conductor 214, normally-closed contacts controlled by armature 253 of relay 249, and through the lower winding of the line relay 215 to battery. The line relay 215 energizes in this circuit, and upon operating at its armature and make contact, completes the circuit of the slow-acting release relay 216. Relay 216 70 thereupon operates and at its armature 217 connects ground to the release-trunk conductor 213 by way of normally-closed contacts controlled by armature 250 of relay 249. Ground is fed to the repeater D by 75 way of release trunk conductor 204, test wiper and release-trunk conductor of selector E1, to the release-trunk conductor 201 of the repeater D. Since there is no high resistance in the release trunk of the connector H, the direct ground will short circuit the relay 141 of the repeater D, which relay 80 will thereupon deenergize and at its armature 196 and resting contact close the shunt circuit about the impulsing armature 184 of the line relay 135 of the repeater D. It 85 can now be seen that with the shunt circuit completed about the impulsing armature 184 that further operation of the line relay 135 will have no effect upon the connector H 90 and the call can be extended no further. In order that this shunt circuit might not be completed around the impulsing armature 184, it is necessary that the calling party 95 the coin-collect mechanism at the paystation A. 100

Returning now to the point in the description where the calling party first operates his calling device S1, a function of the repeater D to improve the impulsing circuit will now 105 be explained. When the line relay 135 of the repeater D first deenergizes in response to the first interruption in its circuit, an impulse of current is transmitted by way of 110 armature 183 and back contact to the slow-to-release relay 137. This relay thereupon energizes and in operating, at its armature 191 and make contact, completes, from 115 ground by way of armature 186, the circuit 120 125 130

of relay 129 through the normally-closed contacts controlled by armature 167 of that relay. Relay 129 thereupon operates and at its armature 167 locks itself to the release-trunk conductor 50, while at its armatures 165 and 168 it short-circuits the upper and lower windings of the differential relay 130 included in the impulsing circuit of the line relay 135. Another result of the energization of the relay 137 is that at armature 190 and its make contact a direct bridge is placed across the trunk conductors 200 and 202 which does not include the upper winding of the relay 133 and the lower winding of the relay 132. These circuit changes are made in order to reduce the resistance and impedance of the switch control circuit to a minimum during the transmission of the impulses.

20 The operation of the system in the case where the subscriber at station A deposits a coin before calling the desired subscriber will now be described and in this connection, the process of collecting the coin at 25 the termination of the conversation will be briefly described. The first operation on the part of the person at substation A is to deposit a coin of suitable denomination in the coin-collecting mechanism provided for that 30 purpose. This mechanism is well understood and its operation need not be explained in detail. When the coin is deposited it descends past the trigger mechanism which is released by the coin with the result that 35 the polarized magnet of the coin-collecting mechanism is connected to the line conductor 12. The coin is held in suspense by a trap-door drop where it is adapted to be either collected or refunded under control 40 of the polarized magnet. The coin may be deposited either before or after the receiver is removed. In either case, the latter operation brings about the operation of the rotary line switch C, whereupon the line is ex- 45 tended to an idle selector as has been described. Assuming that the selector E1, Fig. 3, is the switch to which connection is extended, the operation is the same as has already been described and will not be 50 repeated, with one exception, however; when the line conductors 11 and 12 are connected by the operation of the lineswitch C to the windings of the line relay 135 and the im- 55 pedance coil 139, of the repeater D, the ground on line conductor 12 through the polarized magnet of the coin-collecting mechanism unbalances the differential relay 130 which is included in the line circuit and 60 causes this relay to energize. It may be stated at this point that the polarized magnet at the substation is of high resistance and does not materially interfere with the transmission of operating impulses or with the 65 talking circuit, but it is nevertheless suffi-

cient to cause the relay 130 to operate as described.

Upon attracting its armature 170, relay 130 closes a circuit for relay 134 by way of resting contact and armature 191 and armature 186 and its make contact to ground, which latter relay, upon energizing, establishes a locking circuit for itself at its armature 178 and make contact, locking itself to the release trunk conductor 201. Relay 134, at its armature 181, prepares a circuit which will be described subsequently, and at its armature 180, opens the shunt circuit around the impulsing armature 184, by this last operation obviously permitting the extension of a call regardless of the operated or non-operated condition of the relay 141.

The party at the paystation A may now operate his calling device in accordance with the digits of the number of substation A3. The selector E1 will respond to the first digit to extend the trunk line conductors 200 to 202 into connection with the multiple conductors 203—205, inclusive, of the connector H and the line relay 215 and the slow-acting release relay 216 of the connector H will respond as described. In addition to connecting ground to the release-trunk conductor 213 by its armature 217, the release relay 216 at its armature 218 completes the circuit of the slow-to-release relay 246 by way of armature 224 and resting contact of the ring-cut-off relay 222. Ground is supplied by the armature 218 to the conductor 255 which serves as a holding conductor for the 100 relays in the connector. At its armature 219, relay 216 prepares the impulsing circuit for the magnets of the connector. Relay 246 energizes in the previously-traced circuit and at its armature 248 prepares a locking circuit for itself, and at its armature 247 and make contact prepares the circuit for supplying the booster-battery current from the 105 battery B.

The line relay 215 responds to the first 110 series of impulses received by the connector H through the selector E1 by retracting its armature a corresponding number of times to transmit impulses by way of armature 219 and make contact of relay 216 through the 115 series relay 220 to the vertical magnet 221. The vertical magnet 221 responds to the impulses to elevate the wipers opposite the level of bank contacts corresponding to the level in which the contacts of the line of 120 substation A3 appear, while the relay 220 energizes upon the first impulse and prepares another impulsing circuit for the vertical magnet 221 which is completed when the off-normal springs are closed upon the first vertical step of the switch shaft. The relay 220 is slow to release and consequently remains energized throughout the entire series of impulses.

At the completion of the series of im- 125

pulses, the relay 220 deenergizes and retracts its armature so that when the line relay 215 responds to the next or last series of impulses, the impulses transmitted by that 5 relay will be conducted through the armature and resting contact of relay 220 and thence by way of resting contact and armature 230 of relay 228 to the slow-to-release relay 231 and in parallel to the rotary magnet 254, the impulses to the latter traversing the path including the armature 243 and resting contact of the switch-through relay 237. Relay 231 responds to the first impulse of the rotary series, and at its armature 10 232 connects the test wiper of the connector to the winding of the busy-test relay 228 and at its armature 234, completes an impulsing circuit for the rotary magnet 254 which is independent of the resting contact 15 and armature 230 of relay 228, so that as the wipers of the connector are rotated over contacts of busy lines by the operation of the rotary magnet 254 in response to the impulses delivered by the line relay 215, the 20 connector will not be stopped in engagement with one of these busy lines by the opening of the rotary impulsing circuit at armature 230 of relay 228. When the last series of 25 impulses ceases, the wipers of the connector 30 will be in engagement with the bank contacts to which the line conductors of substation A3 are connected.

If the called subscriber's line is busy at 35 this time, ground will be encountered by the test wiper of the connector and a circuit will be completed from that ground for the busy-test relay 228 since the relay 231 is slow-to-release and will maintain its armature 232 in engagement with its make contact for a short interval after the cessation 40 of impulses. Relay 228 immediately energizes when its circuit is completed, and at its armature 229 prepares a locking circuit for itself which will be completed with the 45 retraction of armature 232 of relay 231 before that armature disengages its make contact, and at its armature 230 it opens the impulsing circuit of the rotary magnet 254 to prevent further operation of that magnet. 50 Relay 228 also connects busy tone to the line conductor 212 through the condenser which tone is heard by the calling party and informs that party that the desired connection is busy.

55 Assuming, however, that when the wipers of the connector H are moved into engagement with the bank contacts of the line of substation A3, the line is idle. Therefore, no ground will be encountered by the test 60 wiper and no circuit will be completed for the busy-test relay 228. Consequently, when relay 231 deenergizes, at its armature 232 and back contact it completes the following circuit for the switch-through relay 65 237: ground through armature 217 and make

contact of relay 216, armature 229 and resting contact of relay 228, lower winding of switch-through relay 237, resting contact and armature 232 of relay 231, test wiper of the connector and the private normal conductor of the line-switch C3 which is individual to the line of substation A3 to battery through the winding of the cut-off relay of that lineswitch. The relay 237 and the cut-off relay of the lineswitch C3 energize in this circuit. The cut-off relay of the lineswitch C3 operates in the well-known manner to disconnect the line relay of the lineswitch from the line and relay 237 at its armature 242 locks itself to the holding conductor 255, at its armature 240 supplies an additional ground to the test wiper of the connector to mark the line of substation A3 busy to other connectors of the group of which connector H is one at its armatures 239 and 245 connects up the ringing generator G to the called line, at its armature 238 connects a ring-back tone to the line leading back to the paystation A to inform the calling party that the desired line is being signalled, at its armature 241 opens a point in the circuit of busy-test relay 228 to prevent any possible operation of that relay, at its armature 243 opens a point in the circuit of the rotary magnet 254, and at its armature 244 opens a point in the circuit of the release magnet 235.

Ringing current from the generator G is now supplied to the called line and the called subscriber is now signalled. When the called subscriber answers, the loop circuit including the called line is completed for the ring-cut-off relay 222 which thereupon operates and at its armature 226 locks itself energized to the holding conductor 255. Relay 222 at its armatures 223 and 227 extends the talking conductors through the connector to the called line, thereby disconnecting ringing current and completing the circuit of the back-bridge relay 249. Relay 222 also at its armature 224 opens the original energizing circuit of the slow-to-release relay 225 and at its armature 245 completes a locking circuit for that relay.

Back-bridge relay 249 energizes when its circuit is completed by the response of the called party and the consequent operation of the ring-cut-off relay 222 and, upon energizing, at its armatures 252 and 253 reverses the connection of the line relay 215 to the line conductors 212 and 214 to reverse the flow of talking current back to the repeater D. Relay 249 at its armature 251 opens the locking circuit of relay 246 which was just completed, and at its armature 250, connects booster-battery current from the battery B to the release-trunk conductor 213. The relay 246 because of its slow-to-release feature remains operated for an interval after its locking circuit is opened by relay

249 and maintains its armature 247 in engagement with its make contact for a short interval. However, relay 246 will deenergize after an interval and at its armature 5 246 disconnect the battery B from the release-trunk conductor 213 and reconnect this conductor to ground through armature 217. Thus, because of the slow-to-release feature of relay 246, an impulse of booster-battery 10 current is sent back to the repeater D over the release-trunk conductor 213 and thence over the multiple 204 to the release-trunk conductor 201.

This reversal in the current flow through 15 the calling line extending through the repeater D causes a reversal of the current flow through the bridge of the repeater, thereby causing the energization of the electro-polarized relay 132. The electro-polarized relay 132 is so adjusted that it will attract its armatures when the current is reversed in its lower winding and will maintain its armature attracted by means of its polarizing winding even if the circuit of 20 its lower winding is subsequently open. However, if the current flow in its lower winding is restored to normal, it will retract its armature. Relay 132, upon operating, 25 at its armature 175 opens a point in the circuit of relay 131, thereby preventing the latter relay from energizing at this time. The lower winding of relay 132 is included in the talking circuit, but, is shunted by the non-inductive resistance 193 which affords 30 a path for voice current so that the talking efficiency of the circuit is not materially affected.

The impulse of booster-battery current connected to the release-trunk conductor 213 40 of connector H and through the selector E1 to the release-trunk conductor 201 extending to the repeater D causes the operation of the booster-battery relay 128 which, upon operating, at its armature 163 locks itself 45 energized through its lower winding to the release-trunk conductor 201. Relay 128, upon operating, also completes the circuit of the slow-acting relay 127 at armature 162, and at armatures 160 and 164 disconnects 50 the incoming line conductors 48 and 51 from the windings of the relay 135 and the impedance coil 139 and extends them direct to the windings of the line relay 215 of the connector H. Another result of the 55 energization of relay 128 is that a circuit is completed from ground by way of front contact and armature 161, conductor 49, bank contact 53, wiper 45, front contact and armature 34, and through the winding of the 60 meter magnet 28 to battery. Magnet 28 operates to register the completed call in the usual manner. Relay 127, upon energizing, at its armature 156 completes an additional holding circuit for the lineswitch 65 C, and at armature 155 prepares certain of

the coin-collect circuits which will be described later.

Conversation now takes place and when terminated, both subscribers replace their receivers upon the switchhooks. When the 70 receiver is replaced at the calling substation A, the line relay 215 in the connector H is deenergized as is the slow-acting relay 216. The latter relay, upon deenergizing, closes a point in the release circuit of the connector 75 H at armature 219 and its resting contact, at armature 217 removes ground from the release-trunk conductor 213, and at its armature 128 removes one ground connection from the connector holding conductor 80 255.

By the removal of ground from the release-trunk conductor 213, the holding circuit of the selector E1 is opened and this switch releases. Ground being removed 85 from the release-trunk conductor 201, one ground connection previously having been removed from that conductor by the release of the relay 136 following the disconnection of the line relay 135 from the calling 90 line by the operation of the booster-battery relay 128, the relays 128 and 132 in the repeater D are deenergized. Relay 132, upon deenergizing, prepares the circuit of the relay 131 at armature 175 and its resting contact. 95

Relay 128, upon deenergizing, opens the circuit of slow-acting relay 127. Before this latter relay has had time to deenergize, an impulse of current is sent over the following path: ground by way of armature 162 and its back contact, armature 157 and its front contact, and thence through the winding of the slow-acting relay 125 to battery. Relay 125, upon energizing, places an additional ground on the release trunk conductor 50, extending back to the lineswitch C, at armature 146, and at armature 147 completes a circuit extending from ground by way of front contact and said armature, conductor 107, through the winding of relay 71, Fig. 2A, to battery. Another result of the energization of relay 125 is that at armatures 145 and 144, both sides of the line of the 100 substation A are opened and at the front contact of armature 144 the battery lead 105 from the battery B2 is connected to the line conductor 12 over the following path: battery B2, resistance lamp L', conductor 105, front contact and armature 155, back contact 105 and armature 177, through the winding of relay 140, front contact and armature 144, conductor 51, bank contact 55, wiper 47, front contact and armature 36, to the line 110 conductor 12. Upon the closure of this circuit, current flows from the battery B2 through the relay 140 and the polarized magnet at substation A in series to ground, energizing both the relay 140 and the polarized magnet. Relay 140 closes at its armature 115 120 and armature 155, back contact and armature 155, front contact and armature 177, through the winding of relay 140, front contact and armature 144, conductor 51, bank contact 55, wiper 47, front contact and armature 36, to the line conductor 12. Upon the closure of this circuit, current flows from the battery B2 through the relay 140 and the polarized magnet at substation A in series to ground, energizing both the relay 140 and the polarized magnet. Relay 140 closes at its armature 125 130

ture 195 a circuit for the slow-acting relay 126. Relay 126, upon energizing, closes at its armature 149 a circuit for the supervisory lamp L5, at its armature 150 completes a locking circuit for the relay 127 which, being slow-acting has not yet deenergized, and at armature 148 connects the interrupter I to the lower winding of relay 133, relay 134 having deenergized when ground was removed from the release trunk conductor 201 and retracted its armature 179.

Ordinarily the polarized magnet at substation A will respond at once to current from battery B2 and will operate to collect the deposited coin and will restore the entire coin-collect mechanism to a normal condition instantly, at the same time disconnecting line conductor 12. However, it sometimes happens that the armature of the polarized magnet sticks and the relay 133 is provided to assure the collection of the coin in such a case. The interrupter I causes relay 133 to vibrate its armature and interrupt the circuit of the battery B2 at its armature 177, or the battery B1 in case this battery is included in the circuit, intermittently energizing the polarized magnet, this operation being ordinarily effective to free the armature in case it should stick. However, should the armature of the polarized magnet continue to stick, the relay 126 will remain energized.

It will be remembered that relay 125, upon energizing, completed a circuit extending from ground by way of front contact and armature 147, conductor 107, through the winding of relay 71 to battery. Relay 71, upon energizing, closes the circuit of the high-resistance relay 69 at armature 91 at armature 93 completes a locking circuit for itself, and at armature 92 closes a circuit which extends over the following path: ground by way of armature 92 and front contact, resistance 97, through the winding of relay 68 to battery. Relay 68, upon energizing, completes a circuit extending from ground by way of front contact and armature 88, through supervisory lamp L3, through the winding of relay 67, and through the winding of relay 66 to battery. Relay 66 is of such high resistance that relay 67 is not energized nor the lamp L3 lighted in series with it though it receives sufficient current to energize. Relay 66, upon operating, completes the circuit of the solenoid 60. The solenoid immediately operates to pull up its plunger arm 75. This operation takes considerable time as the movement of the armature is retarded by means of a dash-pot. The relay 69, upon energizing, closed a circuit for the relay 70 which energized and opened the locking circuit of the relay 71. If the coin is not collected at the substation A, there will still be ground present upon the conductor 107

and the relay 71 will be maintained energized and consequently the solenoid will finally attain its operated position. When this occurs, the springs 77, 78, and 79 will be forced into engagement by the arm 76, completing a circuit extending from battery by way of springs 79, 78, and 77, winding of relay 65, winding of relay 67, lamp L3, armature 88 and its front contact to ground. It will be seen that this circuit short circuits the relay 66 which thereupon deenergizes. The lamp L3 is lighted and the relay 67 operates over this circuit. Relay 67, upon energizing, completes the circuit of the supervisory lamp L2. The lamp L2 is a general supervisory lamp and is common to several groups of switches, while the lamp L3 is individual to a particular group of switches. Relay 67 at its armature 89 also closes the circuit of an alarm, whereby the attention of the exchange attendant is attracted. The attendant, upon seeing the lighted condition of the lamps L2 and L3, will note the nature of the trouble and will go to the particular group of switches designated by the lamp L3. A lamp L5 is individual to each repeater such as D, and by the lighted condition of this signal the attendant will know that it is this particular switch, or rather the coin-collecting mechanism at the paystation, the line of which is associated with this switch, which is causing trouble.

Another condition that this alarm signal provides for is that in case either one of the batteries B1 or B2 is out of order, relay 69 will not be energized and the locking circuit of the relay 71 will be maintained closed even though ground is immediately removed from the conductor 107. Therefore, the signals L3 and L2 will be operated and since there is no lamp similar to lamp L5 operated at this time, the exchange attendant will know the nature of the trouble.

Returning now to the operation of the repeater D, when the polarized magnet of the coin-collecting mechanism at the calling substation is finally disconnected from the line, the relay 140 will deenergize and open the circuit of the relay 126, which relay will deenergize also, thereby opening the locking circuit of the slow-acting relay 127. Relay 127 upon retracting its armature 157 opens the circuit of relay 125 allowing that relay to deenergize. Relay 125, upon deenergizing, removes ground from the conductor 107 at armature 147 and at armature 146 removes ground from the release-trunk conductor 50, whereupon the holding circuit of the switching relay 25 of the lineswitch C is broken. In this manner the line equipment of substation A is restored to normal in condition for another call.

The relay 131 in the repeater D is provided in order to prevent any locking up of

the switches when the called subscriber at the substation A3 replaces his receiver before the calling subscriber does. Assuming the called subscriber to have hung up his receiver 5 before the receiver at the paystation A replaced on the switchhook, the back-bridge relay 249 in the connector H will be de-energized and battery through the lower winding of line relay 215 will be on the 10 lower heavy talking conductor.

The battery flow over the calling subscriber's line is therefore restored to normal and the relay 132 in the repeater D is de-energized to complete the circuit of the 15 relay 131. This circuit extends from ground by way of armature 162 and make contact of relay 128, which relay is in its operated position since ground has not been removed from the release-trunk conductor 201, back 20 contact and armature 175 of relay 132, and then through the winding of relay 131 to battery. Relay 131, upon energizing, reverses the conductors 202 and 200 with regard to the subscriber's line at its armatures 25 172 and 173 in order to prevent the line relay 215 of the connector H from remaining energized in series with the polarized magnet at the subscriber's station A after the calling subscriber hangs up. When the calling 30 subscriber hangs up, the release of the connection and collection of the coin will take place in the manner as before described.

Returning now to the operation of the connector H, it will be assumed that the calling 35 subscriber at paystation A replaces his receiver upon the switchhook before the called subscriber at substation A3 does. The line relay 215 immediately deenergizes and opens the circuit of the slow-acting relay 216. 40 Since the back-bridge relay 249 is still in its energized position, ground will be present upon a holding conductor 255 by way of armature 225 and make contact of cut-off relay 222 and armature 251 and make contact of relay 249. Therefore, the connector H will be held until the called subscriber 45 hangs up. When this takes place, the back-bridge relay 249 will energize and remove ground from the holding conductor 255 thereby opening the locking circuit of relays 50 222 and 237. Relay 237 upon deenergizing retracts its armature 244 to complete the circuit of the release magnet 235 which circuit is as follows: ground by way of armature 55 219 and resting contact of line relay 215, armature 244 and resting contact of relay 237, off-normal springs 236, through the winding of release magnet 235 to battery. 60 The release magnet 235 thereupon energizes and restores the connector H to normal in the well-known manner.

In case the called subscriber does not answer or the calling party at the paystation A hangs up before the called subscriber

answers, it will be necessary to refund the deposited coin rather than collect it. In either case, when the calling party replaces the receiver the refund operation must be initiated. This refunding operation will now be explained. Since the called subscriber did not answer, neither the booster-battery relay 128 nor the polarized relay 132 are energized and no circuit will have been completed for the slow-acting relay 127 70 or the meter magnet 28 associated with the lineswitch C. Therefore, when the calling subscriber hangs up his receiver, the line relay 135 deenergizes and sends an impulse of current to the slow-acting relay 137, at the 80 same time opening the circuit of slow-acting relay 136. Relay 136 thereupon deenergizes and completes the following locking circuit for the relay 137: ground by way of armature 162 and resting contact of relay 128, 85 armature 185 and resting contact of relay 136, armature 181 and make contact of relay 134, through the winding of relay 137 to battery. Relay 135, upon deenergizing, at its armature 184, opens the bridge circuit, thereby causing the release of the selector E1 and the consequent removal of ground from the release-trunk conductor 201, thereby unlocking the relay 134 since one ground connection was also removed from the release-trunk 90 conductor 201 by the retraction of armature 188 of relay 136.

Relay 134, upon deenergizing, at its armature 181 opens the locking circuit of relay 137. Before relay 137 has had time to retract its armature, an impulse of current is transmitted from ground by way of armature 162 and its resting contact, armature 185 and its resting contact, armature 181 and its resting contact, make contact and armature 192 of relay 137, and thence through the winding of relay 125 to battery. Upon energizing, relay 125 operates as before described, except that in the present case since relay 127 is deenergized, the battery lead 106 from the battery B1 is connected to the line conductor instead of the battery lead 105 of the battery B2. Current flow from the battery B1 now operates relay 140 and the polarized magnet at the calling substation A in series, the polarized magnet now being actuated to refund the deposited coin rather than collect it. Upon energizing, relay 140 completes the circuit of slow-acting relay 126 which operates to 115 close the holding circuit of relay 125 by way of armature 150 and make contact and armature 158 and resting contact of relay 127. The energization of relay 126 also produces 120 certain other circuit changes which have been 125 explained before.

When the circuit is broken by the polarized magnet at the calling substation being disconnected from the line conductor 12, the relay 140 deenergizes and opens the cir- 130

cuit of relay 126 which deenergizes also. As a result of the deenergization of relay 126, the holding circuit of relay 125 is opened and this relay restores to normal, thereby 5 removing ground from the holding conductor 50 to allow the lineswitch C to restore to normal, thereupon all the apparatus will have been released.

Should the coin-collecting mechanism at 10 the paystation fail to refund the coin, the supervisory equipment of Fig. 2A will function as before described to indicate to the exchange attendant such failure. By the lighted condition of one of the lamps L 15 and L1, Fig. 2A, the attendant will know which of the batteries B1 and B2 is connected to the circuit and will therefore be able to tell whether the paystation apparatus is at fault in refunding or collecting the coin.

20 Let it be assumed now that the calling party at the paystation A desires to converse with an official or an employee of the telephone company other than an operator such as a recording operator, for which 25 type of call no charge is to be made. This type of call, however, requires that a coin first be deposited in the coin-collecting mechanism at the paystation A before the call is initiated as in the case of the call from the 30 paystation A to the subscriber A3. Let it further be assumed that the desired official, or employee, is the one whose telephone is represented by the substation A4, Fig. 3. Inasmuch as substation A4 is accessible to 35 the connector H1 and that connector is accessible to the selector E1 over the tenth level of its bank contacts, the party at the paystation A after depositing the proper coin operates the calling device S1 for the 40 digit 0 thereby causing the repeater D to repeat ten impulses to the selector E1 in the manner previously described.

The selector E1 in response to these ten impulses elevates its wipers opposite the 45 tenth level of bank contacts and then automatically rotates its wipers step by step over the contacts in the tenth level until an idle connector is found. Assuming the connector H1 to be the first idle connector found 50 by the selector E1, the selector E1 upon placing its wipers on the contacts to which the conductors 209 to 211, inclusive, are connected, will perform its switching-through operation to connect the repeater D through 55 to the connector H1 so that the next series of impulses repeated by the repeater D in response to further operation of the calling device S1 at the paystation A will cause the connector H1 to respond in a manner 60 similar to that in which connector H responded, to connect the paystation line to that of the substation A3.

When such connection has been completed 65 and the party at station A4 has responded to the ringing of his call bells by ringing

current sent out over the called line by the connector H1, the connector H1 will function to reverse the flow of current over the line conductors 200 and 202 extending back to the repeater D, but since, as previously 70 stated, the connector H1 is not provided with means for transmitting a booster-battery impulse over the release-trunk conductor 201, the repeater D will be effected only by the reversal of current flow. Therefore, 75 the polarized relay 132 in the repeater D will operate responsive to the current reversal, but the booster-battery relay 128 will not operate. The only function performed by the polarized relay 132 upon operating is 80 the opening of the circuit of the relay 131 at the contacts controlled by armature 175.

Since the relay 128 does not operate in this connection, the relay 127 will remain inert and the release of the connection by 85 either the calling or called subscriber causes the operation of the relay 125 which thereupon functions to connect the coin-refund battery B1 to the paystation apparatus, since relay 127 is not operated, as previously 90 explained. The coin-collecting mechanism at the paystation A thereupon functions to refund the coin to the calling party and to disconnect the polarized magnet of the coin-collecting mechanism from the line conductor 12 to cause the release of the lineswitch 95 C as in the case of the previously-described connection. Thus the calling party has been able to call an official or an employee of the telephone company and at the end of the 100 conversation have his coin returned to him.

When a fire or police call, or a call to a recording or similar operator, is made from the paystation A, it is not necessary that the calling party deposit a coin in order to make 105 the call because of the high resistance release trunk of the selector E1 and because the special selector accessible to the selector E1 for calls of this type is also provided with a high-resistance release trunk, thereby preventing the relay 141 in the repeater D from being short-circuited at any time. Since relay 141 remains operated throughout the entire connection, by maintaining its armature 196 out of engagement with its 110 resting contacts, that relay maintains open the shunt circuit around the impulsing armature 184 of the line relay 135. It is only when all switches in a switchtrain are 115 equipped with a high resistance in the release trunk that calls may be made without the necessity of first depositing a coin.

When the subscriber at the substation A2 initiates a call, the lineswitch C2 individual to the line of the substation A2 functions in the usual manner to select a trunk leading to an idle selector switch such as the selector E2. When substation A3 is the "called" 120 station desired by the subscriber at substation A2, the selector E2 will function in the 125 130

usual manner responsive to the operation of the calling device S2 to select the trunk conductors of an idle connector switch such as the connector H. When the selection has 5 been completed the selector E2 will extend the calling line to the connector H, which latter switch will then operate as has already been described in response to the next two series of impulses transmitted by the calling 10 device S2 to connect the calling line to the substation A3. When the called subscriber answers the call, the connector H besides reversing the direction of current flow in the line of substation A2, which reversal has no 15 particular effect in this connection, transmits a booster-battery impulse over the release trunk of the calling line to the meter M associated with the lineswitch C2. The meter will thereupon be operated to register 20 the call.

When the party at substation A4 is the one with whom the subscriber at station A2 desires to converse, the selector E2 will be 25 operated to select an idle connector of the group in which the connector H1 belongs. The connector H1 will thereupon be operated in the usual manner to extend the calling line to the substation A4 and upon the response of the called party will connect 30 the calling line through to the line of substation A4 and will reverse the direction of the current flow in the calling line without any particular effect. Since connector H1 is not arranged to transmit a 35 booster-battery impulse, the meter M of the calling line will not be operated and no registration of the call to the substation A4 will be made.

When the toll operator at the position in 40 which the jack J is located inserts the plug of a cord circuit in the jack J, the lineswitch C1 functions as usual to connect the toll trunk to an idle selector switch such as the selector E2. The selector E2 operates 45 upon the transmission of impulses to select a connector switch such as either the connector H or the connector H1 corresponding to the number of impulses received. Since both of the connectors H and H1 reverse 50 the direction of current flow in the calling line upon the response of the called party, the answering supervisory signal of the cord circuit attached to the jack J will be operated and the operator will thereby be able 55 to know when the called party has responded. If the call is made to one of the officials or employees of the telephone company, for example, the one whose station is designated as A4, and the connector H1 employed 60 in the connection, the operator would have to listen in on the line to determine when the called party responded if the connector H1 did not reverse the direction of the current flow in the calling line upon the 65 response of the called party.

From the foregoing it will be appreciated that if the relay 128 of the repeater D were operated by the reversal of current in the calling line by the connector that the connector H1 could not be employed in a connection between the pay station A and substation A4 without the coin deposited by the calling party being collected upon the termination of the connection. It would, therefore, be necessary to provide a connector which did not reverse battery feed upon the response of the called party for free connections between the paystation A and the substation A4. This special connector could not be used for connections between the toll operator and the substation A4 since the toll operator would have no answering supervision without the reversal of current in the connecting trunk. Since, in the present invention the coin-collect operation of the repeater D is dependent upon the impulse of booster battery caused by the operation of the connector in response to the answering of the called party, the special connectors may be omitted and the number 80 of connectors reduced, thereby simplifying the automatic telephone system and increasing the operating efficiency of these two groups of switches. 85

The invention having been thus described, what is considered new and what it is desired to have protected by Letters Patent will be pointed out in the claims which follow. 90

What is claimed is:

1. In a telephone system, a calling line having a coin-collecting mechanism including an operating magnet therefor, a called line, an automatic switch, means whereby said calling line can extend a connection to said called line via said switch after a coin has been deposited in said mechanism, means in said switch responsive to the answering of the called party for transmitting an impulse of booster-battery current, and means operated by said impulse for operating said magnet to manipulate said mechanism to collect the deposited coin. 105

2. In a telephone system, a calling line having a coin-collecting mechanism, a called line, an automatic switch, means whereby the calling line can extend a connection to the called line via said switch after a coin has been deposited in said mechanism, means in said switch responsive to the answering of the called party for transmitting an impulse of booster-battery current, and means partially operated by said impulse and completely operated responsive to the breaking of said connection for operating said mechanism to collect the deposited coin. 115

3. In a telephone system, a series of automatic switches including a paystation repeater for connecting a calling paystation line having coin-collecting mechanism and 120 125 130

a called line in a conversational circuit, means in the final switch for transmitting an impulse of booster battery current to said repeater when the called party answers, 5 means in said repeater for collecting or refunding a coin deposited in said mechanism when said circuit is broken, and means in said repeater operated by the impulse of booster-battery current for conditioning said 10 collecting or refunding means to collect the deposited coin.

4. In a telephone system, a calling line having paystation equipment, an automatic switch in the exchange, a booster battery in 15 the exchange, a called line, a repeater interposed between said calling line and said switch and having means for operating said equipment to collect and refund deposited coins, means for extending a connection 20 from said calling line through said repeater and switch to said called line after a coin has been deposited in said paystation equipment, means in said switch responsive to the answering of the called party for transmitting an impulse of current from said 25 booster battery to said repeater, and means in said repeater operated by said booster-battery current impulse to prepare said repeater to collect the deposited coin responsive to the breaking of the established 30 connection.

5. In a telephone system, a calling line, a paystation device connected thereto, a called line, automatic switches at the 35 exchange, a repeater interposed between the calling line and said switches and having means for controlling said device to collect and refund deposited coins, a control circuit for said repeater, means for operating said 40 repeater and said automatic switches to establish a connection from the calling line to the called line after a coin has been deposited in said device and to extend said control circuit to the last of said switches, 45 means in the last of said switches responsive to the completion of the established connection for transmitting an impulse of booster-battery current over said control circuit to said repeater, and means in said repeater operated by said impulse for causing said repeater to control said device to collect the 50 deposited coin when said connection is broken.

6. In a telephone system, a calling line, a paystation coin device connected thereto, 55 a paystation repeater, two automatic switches having release trunks, one of said switches having means for transmitting an impulse of booster-battery current over its release trunk responsive to the completion of 60 a connection established to a called line, means operated by said repeater under control of said calling line for selecting a desired one of switches, the selected switch then operated by said repeater to connect 65 the calling line to a called line, means in said

repeater for collecting and refunding coins deposited in said coin device responsive to the release of a completed connection, and means in said repeater for conditioning said last means to collect a deposited coin responsive to the reception of an impulse of booster-battery current when said one switch is the selected switch.

7. In an automatic measured-service telephone system in which selectors and booster-battery connectors are employed to extend connections between calling paystation lines and called lines after a coin has been deposited in the coin-collecting mechanism at the paystation, a paystation repeater associated with each selector, said repeater having means for operating a selector and a connector to establish a connection between a calling paystation line and a called line, means for collecting a deposited coin, and means operated by an impulse of booster-battery current from said connector responsive to the completion of the extended connection for preparing said coin-collecting means for operation and operating that means when the connection is broken.

8. In a telephone system, a calling line, a paystation device connected thereto, a called line, automatic switches including a booster-battery connector switch at the exchange, a repeater interposed between the calling line and the automatic switches, a control circuit for said repeater, means for operating said repeater and said switches to establish a connection between said calling line and said called line and to extend said control circuit to said connector after a coin has been deposited in said device, means in said connector responsive to the completion of the established connection for transmitting an impulse of booster-battery current over said control circuit to said repeater, means in said repeater for operating said paystation device to collect a deposited coin, and a relay in said repeater operated by said booster-battery current impulse for preparing said paystation device operating means for operation and then operating it when said connection is broken to collect the deposited coin.

9. In a telephone system, a calling line, a paystation device connected thereto, a pair of automatic switches, means whereby the calling line can extend a connection via either switch to a called line after a coin has been deposited in said device, means in one of said switches responsive to the answering of the called party for transmitting an impulse of booster-battery current, means rendered effective by the booster-battery impulse to collect the deposited coin upon the termination of a connection extended via said one switch, said last means effective to refund the deposited coin upon the termination of a connection extended via the other switch.

10. In a telephone system, a calling line, a

- paystation device connected thereto, a first called line for calls to which a charge is made, a second called line for calls to which no charge is made, a pair of automatic 5 switches, means in one of said switches responsive to the answering of a called party for transmitting an impulse of booster-battery current, means whereby the calling line after a coin has been deposited in said device 10 can extend a connection to said first called line via said one switch or extend a connection to the second called line via the other switch, and means effective on the termination of a connection extended to the second 15 called line via said other switch for refunding the deposited coin, said means rendered effective by the booster-battery impulse to collect the deposited coin upon the termination of a connection extended to the first 20 called line via said one switch.
11. In a telephone system, a calling paystation line having coin-collecting mechanism, a calling subscriber's line having a call meter, a manual operator's trunk line, 25 all of said lines terminating in the same automatic exchange, a repeater-selector link available to the paystation line, a selector available to said trunk line and said subscriber's line, one connector provided with 30 means for reversing the direction of flow of talking current to a calling line responsive to the answering of the called party, another connector provided with means for reversing the flow of talking current to the calling 35 line and also provided with means for transmitting an impulse of booster-battery current over the release trunk of the calling line responsive to the answering of the called party, means whereby said paystation 40 line can extend a connection by way of said repeater-selector link and either one of said connectors after a coin has been deposited in the coin-collecting mechanism, means in said 45 repeater conditions for operation by the booster-battery impulse when said other connector is employed in the extension of a connection to a called line and operated when said connection is broken to collect the deposited coin and effective when the connection 50 is extended to a called line by said one connector and subsequently broken for refunding the deposited coin, means whereby said subscriber's line can extend a call by the selector and either one of said connectors, means associated with said meter responsive to the impulse of booster-battery current when said other connector extends the call to a called line for operating said 55 call meter but ineffective to operate said 60 meter when said one connector extends the call to a called line, and means whereby said operator's line can extend a call via the selector and either one of the connectors, and means associated with the operator's 65 line responsive to the reversal of current by either connector for providing answering supervision.
12. In a telephone system, a calling line having a coin collector, relay means for controlling said collector to collect and to refund coins deposited therein, an automatic switch, a called line, means whereby said calling line can associate said relay means with said switch and operate said switch to extend a connection to said called line after a coin has been deposited in said collector, means in said switch for transmitting a booster-battery impulse responsive to the answering of the called party, and means operated by said impulse to condition said relay means for controlling said collector to collect the deposited coin. 70 75 80
13. In a telephone system, a calling line provided with a coin collector, a called line, a series of automatic switches including a paystation repeater, means whereby said calling line can extend a connection to said called line via said repeater and switches after a coin has been deposited in said collector, means in said repeater for operating said collector to collect and to refund coins, a source of special current associated with the final switch of said series, means in said final switch responsive to the answering of the called party to momentarily substitute 90 95 said special current for the regular current of the system in the release trunk conductor of the connection through said switches and repeater, a relay in said repeater connected to said release conductor and unresponsive to the normal current therein but responsive to said special current therein to condition said collector operating means for its collecting operation, and subscriber controlled means for operating said conditioned means 100 105 to operate said collector to collect the deposited coin.
14. In a telephone system in which the coin collector of a calling paystation line is controlled to collect a deposited coin by the application of a special current of one polarity thereto and to refund a deposited coin by application of a special current of another polarity thereto, a paystation repeater having means responsive to the breaking of a connection by the calling line to apply one or the other of said special currents to said coin collector to either collect or refund the deposited coin according to whether or not said connection is completed, 110 115 120 a connector switch, means whereby the calling line can extend a connection comprising talking strands and a release conductor through said repeater and switch to a called line, means in said connector responsive to the completion of the connection by the answering of the called party to transmit an impulse of booster current over said release conductor to said repeater, and means in said repeater operated by said impulse to 125 130

condition said current applying means to apply the special current of said one polarity to said collector upon the breaking of the completed connection to collect the deposited 5 coin.

In witness whereof, I hereunto subscribe my name this 13th day of January, A. D. 1931.

VICTOR S. THARP.
